UNITED STATES PATENT OFFICE.

GEORGIA P. SHEARER, OF PALO ALTO, CALIFORNIA.

DESIGN FOR A BASKET.

Application filed October 10, 1921. Serial No. 506,892. Term of patent 3½ years.

To all whom it may concern:

Be it known that I, GEORGIA P. SHEARER, a citizen of the United States, and a resident of Palo Alto, county of Santa Clara, State of California, have invented a new, original and ornamental Design for a Basket, of which the following is a specification, reference being had to the accompanying drawing, forming part thereof.

I claim:

The ornamental design for a basket, substantially as shown.

GEORGIA P. SHEARER.
